UNITED STATES PATENT OFFICE.

THOMAS J. CREAGHEAD, OF COVINGTON, KENTUCKY.

INSULATOR-SUPPORT.

No. 878,870.

Specification of Letters Patent.

Patented Feb. 11, 1908.

Application filed May 19, 1902. Serial No. 108,057.

To all whom it may concern:

Be it known that I, THOMAS J. CREAGHEAD, a citizen of the United States, residing at Covington, in the county of Kenton and State of Kentucky, have invented certain new and useful Improvements in Insulator-Supports, of which the following is a full, clear, and exact description, reference being had to the accompanying drawing, forming 10 part of this specification.

My invention relates to insulator supports for electrical conductors and it has for its object, to furnish a substantial and durable support of such size as to be adapted to 15 carry strains of considerable magnitude and yet one which can be readily and easily secured to an ordinary cross arm, or other support, by a bolt of such comparatively small diameter passing through or into 20 the support, as not to unduly weaken the same.

The essential feature of my improvements consist of a malleable iron, bronze, or other casting, having a wide base extending into 25 longitudinal strengthening ribs tapering upwardly and terminating in a head and provided with means for properly securing the insulator thereto, in connection with a bolt of comparatively small diameter of wrought 30 iron or other suitable material, the securing bolt, being arranged to pass through the cross arm and to screw into, or be otherwise secured to the base of the insulator support to fasten the insulator thereto.

35 In the drawings: Figure 1 is a vertical section, partly in elevation, of my improved insulator support. Figs. 2 and 3 are cross sections of the support taken on lines 4—4 and 5—5 respectively of Figure 1.

40 A is the insulator support of malleable iron, bronze, or other cast metal, provided with a broad base *s* having a foot flange *a*. Extending from the base are longitudinal strengthening ribs *b*, *b*, which taper upwards 45 and terminate in a transverse web or cap-piece *c* forming with the portions of the ribs adjacent thereto a series of recesses or seats at the top of the support for the reception 50 of the material of a thimble or other insulator attaching means, such attaching means being molded or otherwise formed about the trans-

verse web and portions of the ribs and increasing the same.

Upon the head *c* and engaging the portions of the strengthening ribs *b*, *b* adjacent thereto, is mounted a thimble *a'* of suitable soft material, preferably lead or other soft metal, which may be cast or molded thereabout, to form an attaching means and cushion for the insulator *B*. By this construction it will 60 be seen that, as portions of the ribs *b*, *b*, and the head *c*, are incased in the thimble, the latter is prevented from turning or working off.

d is a threaded recess formed in the base of the insulator support to receive the screw-threaded end of the bolt *C*, which passes through the cross-arm and is secured thereto by the nut *e* and washer *f*.

Upon the principles of the lever, the amount of strain upon the bolt *C* under any 70 given pull of wire upon the insulator, varies inversely as the distance of the bearing point in the base of the insulator support from the point of strain in the bolt. To insure the removal of this point of bearing as far as possible from the bolt, and overcome the disadvantages arising from unevenness in the base of the ordinary broad based supports, or in the surfaces of the cross-bars to which they are attached, I have constructed the 80 broad base *s* with a projecting bearing surface *a* at its outer edge whereby the strain is necessarily thrown at a point removed from the bolt and the purposes of a broad base made effective.

Having thus described my invention what I claim and desire to secure by Letters Patent is—

A metal insulator support comprising a stem provided with longitudinal strengthening ribs and a transverse web or cap-piece to which said ribs extend, a thimble of soft metal or other material molded about said web and portions of the ribs, whereby said thimble is secured against rotary movement 95 and vertical displacement, and means for securing said stem to a cross-arm or other support.

THOMAS J. CREAGHEAD.
